METHOD OF FORMING WHEELS

Warren H. Farr, Detroit, Mich., assignor to Budd
Wheel Company, Philadelphia, Pa., a corpora-
tion of Pennsylvania

Application July 8, 1932, Serial No. 621,417
Renewed October 12, 1936

2 Claims. (Cl. 29—159.03)

My invention relates to methods of fabricating metal wheels, particularly of the pressed metal artillery type.

A primary object of my invention is to fabricate wheel parts, particularly the spokes of an artillery wheel, by a means and in a manner that shall be more accurate in holding the metal-gauge thickness and forming the contours of the parts, and that shall have other advantages.

Another object of my invention is to form metal wheel parts by less actual rolling and other effort than in the usual methods of forming such parts.

Broadly, the invention comprises the method of rolling a wheel blank radially, or progressively pressing it along perimetral-spaced radial paths to produce radial formations, ribs or spokes thereon.

In effecting this result, a pair of die-pressing rolls, having any desired perimetral and axial contours, are arranged to receive the discs or spider spokes therebetween, whereby to vary the disc or spider gauge and to press the spokes, ribs or other formations to uniform or varied radial section and any suitable axial section.

A movable carriage, on which the blank is mounted, is normally biased toward the rolls. A cam and plunger structure controls the biasing means, whereby the carriage moves toward and away from the roll at periodic intervals. An indexing device, mounted on the carriage base, provides step-by-step turning movement of the blank about its axis, between the rolling operations.

The arrangement is such that the blank lies in a plane directed through a position between the rolls. At a predetermined position of the rolls about the axes thereof, the cam releases the carriage to thrust the blank in the direction of its plane between the rolls, whereupon the rolls travel outwardly along the blank to simultaneously press the same and force it away from the rolls. As this action is completed, the cam engages the plunger to temporarily hold the carriage in its outermost position. At the beginning of the return or feeding movement of the carriage, the blank is turned about its axis, through an angle equal to the distance between its spokes or other formations, thus presenting another blank portion for rolling, as in the first described instance; this operation being repeated automatically until all of the forming operations are completed.

The invention will be better understood from

a consideration of the accompanying drawings, in which,

Fig. 1 is a side view, partially in elevation and partially in section, of a machine for practicing the method of my invention.

Fig. 2 is a top plan view of the device shown in Fig. 1.

Fig. 3 is a view, similar to Fig. 1, showing the parts as positioned at the beginning of a rolling operation.

Fig. 4 is a detail view, in perspective, of a spoke of one form which may be made in the machine of the other figures.

Fig. 5 is a view taken substantially along the line 5—5 of Fig. 1.

Figs. 6 and 7 are views, in axial section and in side elevation, respectively, of a wheel part which may be fabricated according to the method of my invention, and

Fig. 8 is a view, in section, of die-press rolls of modified form for shaping the structure of Figs. 6 and 7.

Referring particularly to Figs. 1, 2, 3, and 5, the machine comprises a base 7 of any suitable character, such as the inverted substantially trough-shape illustrated, a standard thereon having laterally-spaced portions 8 extending perpendicularly therefrom, a carriage support 10 on the base 7, a carriage 12 having side flanges in grooves 13 of the support 12, a blank-receiving pin 14 mounted on the carriage, an index lever support 15 mounted on the carriage support 10 at one side of the carriage, a member 16 on the carriage 12, for supporting a lever 18 that carries a roller 21 engaging a star wheel 17 on the pin 14, a pin 19 extending between the sides of the carriage 12 at the under side thereof, a lever 20 having bifurcated end 22 embracing the pin 19, a pin or shaft 24, extending between the sides of the base 7, for pivotally mounting the lever 20, 40 a cross beam 26, in the base 7, supporting a bearing 27 for a plunger 28 and having a projection 29 on said bearing, a spring 30 extending between the lever 20 and the projection 29, and a wearing plate 32 on the lever 20.

Rolls 35 are mounted on shafts 36 that are journaled between the standard portions 8 and connected, through a suitable gear-wheel train 37 to a motor 38 in the base 7. The gears 37 also extend between the motor 38 and a cam 40 that is mounted on a shaft 42, opposite the plunger 28.

As indicated more clearly in Fig. 2, a spoke 44 is directed along a line, in a plane between the

adjacent pressing surfaces of the rolls 35. The blank is accurately held in this position by the star wheel 17 that is engaged by the roller 21 on the lever 18. The latter is pivotally mounted 5 on the member 16 and biased toward the star wheel 17, as by a spring 48.

The indexing device comprises a dog 50 that is pivotally mounted, by a pin 51 on the member 15, and biased to the left, as viewed in Fig. 1, by 10 a spring 52 that is secured to a stationary pin 53. The dog 50 extends vertically in the path of movement of the arms of the spider, so that, when the carriage moves to the right, as viewed in Fig. 1, it is carried with the spider to slip 15 from under the adjacent spoke, so that the position of the spider is unaffected. On the return movement of the carriage, the dog 50, being in the path of one of the spokes and not movable to the left, as viewed in Fig. 1, it thus turns the 20 spider about its axis, through an angle, equal to the distance between two of the spokes, to position a succeeding spoke for the rolling or progressive pressing operation.

The accentuating device, including the star 25 wheel 17 and the roller 21, while firmly holding the spider in position, may be forcibly released by engagement of the spider with the indexing device. Other means may be provided to hold the spider in position, the means shown being 30 merely illustrative of one form which may be employed.

In operation, with the parts related as indicated in Fig. 1, the cam 40 rotates clockwise, as indicated by the arrow in Fig. 1, and moves off 35 the head of the plunger 28 to thereby permit the spring 30 to move the lever 20 clockwise about its pivot shaft 24. This action permits the lever end 22, through its lost motion connection to the pin 19, to move the carriage 12 forwardly to 40 a position, indicated in Fig. 3, wherein the blank will be engaged, at the radially inner end of one of its spokes, by the rolls 35 which rotate in directions indicated by arrows thereon; the cam 40 continuing to rotate clockwise during the 45 spoke-rolling operation.

Also, during this operation, the blank is forced by, and away from the rolls against the action of the spring 30, thus insuring proper holding relation between the rolls and the blank. In the 50 meantime, the leading face of the cam 40 has taken up a position, adjacent to the head of the plunger 28 to again hold the blank against movement toward and to move the blank further away from the rolls, during which movement the blank 55 is again indexed to place a new spoke in position

the blank is released and fed toward the rolls and the action above described is repeated.

In Fig. 4, a spoke of relatively simple channel section illustrates one form which may be readily formed by comparatively simple roll shapes.

In Figs. 6 and 7, a spider is shown having a hub portion 55, spoke portions 56 and radial side ribs 57. The spider has a wheel plane portion 58 of radially-outwardly-converging-tapered gauge, also extending along the spokes. The ribs 57 extend from the hub outwardly along the spokes substantial distances along curved lines. The ribs 57 and the tapered-gauged wheel-plane portions of the spokes may readily be formed, in one operation, according to the method and by 15 the machine of my invention, by suitably shaping the rolls 35, as indicated in Fig. 8. In this figure, the section corresponds to a section taken substantially along lines 8—8 of Fig. 6, it being understood that the roll section varies in accordance with the section at the blank from the radially inner portion thereof, having a heavy-gauge wheel-plane portion and extensive axial rib sections, to and beyond the radially outer portion, where the ribs disappear; the rolls forming both 20 the wheel-plane gauge and the axial and radial contours of the ribs.

While I have shown and described a particular phase of my invention, changes may be effected therein without departing from the spirit and scope thereof, as set forth in the appended claims.

What I claim is:

1. The method of forming spoked wheel bodies which comprises providing a blank comprising a 35 hub portion and integral, radially extending, substantially untapered spoke portions, and then simultaneously tapering and contouring said spoked portions by a radial rolling operation as to each spoke along the extent of each spoke to 40 form a rolled grain therein extending substantially only in one direction and in the line of extension of the spoke.

2. The method of forming wheel spiders which comprises forming a metal blank to a spider 45 shape, comprising a substantially tubular hub barrel portion and a plurality of radially extending spoke portions transversely to the axial extent of the hub portion, and radially rolling the spoke portions of said blank in a manner to 50 provide a tapering thickness radially of said spoke portions and to simultaneously provide in said spoke portions radially extending ribs of tapering depth, the ribs being transversely extending as respects the initial plane of the spokes per se. 55

WARREN H. FARR.
